(57) **CLAIM**

I claim the ornamental design for a camera bag, as shown and described.

DESCRIPTION

FIG. 1 is a front view of a camera bag showing my new design;

FIG. 2 is a right side elevational view thereof;

FIG. 3 is a left side elevational view thereof;

FIG. 4 is a rear view thereof;

FIG. 5 is a top plan view thereof; and,

FIG. 6 is a bottom plan view thereof.

The broken line shown in FIGS. 4, 5, and 5 illustrate the portions of the design that form no part of the claim.
